UNITED STATES PATENT OFFICE.

SAMUEL COHN, OF NEW YORK, N. Y., ASSIGNOR OF ONE-HALF TO AUGUST CAPLAN, OF SAME PLACE.

SEWING-MACHINE FOR GATHERING THE MOUTHS OF TUBULAR STRUCTURES.

SPECIFICATION forming part of Letters Patent No. 678,542, dated July 16, 1901.

Application filed June 8, 1900. Serial No. 19,548. (No model.)

To all whom it may concern:

Be it known that I, SAMUEL COHN, a citizen of the United States, residing in the city, county, and State of New York, have invented certain new and useful Improvements in Sewing-Machines for Gathering the Mouths of Tubular Structures, of which the following is a specification.

My invention relates to sewing-machines, and has for its object to produce a sewing-machine adapted for the sewing of the mouths of bags and other analogous uses, although my invention is not limited to the character of work for which the machine may be employed.

The invention will be described with reference to the accompanying drawings, which show by way of illustration a machine embodying my invention.

20 In the drawings, Figure 1 is a side elevation of the machine. Fig. 2 is a plan view thereof; Fig. 3, an end elevation of the machine, showing the grasping-jaws open; and Fig. 4 is a similar end elevation of the machine showing the jaws closed.

The machine shown in the drawings, which is merely one of the various forms and structures in which my invention may be embodied, preferably consists of a suitable base *a*, upon which are mounted standards *b* *b'* *b''*. Pivoted in these standards by pivots *c* are jaw-carrying arms *d*, which jaw-carrying arms are provided with pins *e* at or near their lower ends which enter slots *f* of a cam-plate *g*, carried upon the main operating-shaft *h* of the machine. The jaw-carrying arms *d* carry suitable grasping jaws or carriers *i* *j*. (Best seen in the plan view, Fig. 2.) The jaw *i* is provided with suitable teeth *i'*, with intervening depressions, and the jaw *j* is provided with suitable teeth *j'*, with intervening depressions. These teeth are provided with slots *i''* in the case of the teeth *i'* and *j''* in the case of the teeth *j'*.

45 Mounted upon the framework of the machine—to wit, the standards *b'* *b''*—is a suitable toothed member or folder *k*, having at both sides thereof teeth *k'*, with which mesh the teeth *i'* of the jaw *i* and the teeth *j'* of the jaw *j*. The said teeth are slotted, as shown at *k''*, which slots come opposite the slots *i''* in jaw *i* and slots *j''* in the jaw *j*, so as to leave

a clear passage between the jaws and the toothed member or folder for the passage of needles. In the present instance I have shown two needles *l*, which are adapted to pass through the slots and the teeth of the jaws and toothed member or folder. These needles are preferably removably carried upon a suitable needle-carrier *m*, which is adapted to slide upon guides or guide-rods *o*, carried on the framework of the machine between the standards *b* and *b'*. An adjustable guide-plate *p* is provided upon the guide-rods, which guide-plate is suitably slotted to form a guide for the points of the needles. The needle-carrier *m* is pivotally connected to a bell-crank lever *q*, which is pivoted at *r* upon a bracket *s*, and is pivotally connected by means of a suitable link *t* to an arm *u*, carried upon the main shaft of the machine. When the jaws are open, as shown in Fig. 3, the arm *u* is in such position that the link *t* is on a dead-center, so that as the shaft *h* turns the jaws will be closed before the needle-carrier begins to move.

The operation of the structure is as follows: A bag-mouth with a suitable hem turned up is placed over the toothed member or folder *k*. The operating-handle *v* or other operating means is turned toward the right in Fig. 3, thereby rocking the shaft *h* and causing the cam-slots *f* in the cam-plate *g* to close the jaws firmly against the toothed member or folder *k*. While this operation is taking place the link *t* is being swung idly on the pivot *w*, which forms its pivotal connection with the bell-crank lever *q*, it being remembered that the link *t* is on a dead-center in Fig. 3, so that some lost motion will take place while the jaws are being closed against the folder. The jaws closing upon the bag-mouth force the same into an undulating shape between the opposing meshed faces of the teeth *i'* *k'* and *k''* *j'*. As the operating means *b* continues to move the needles will be moved forward by the needle-carrier, will enter the slots of the jaws and folder, and will pass through the undulating portions of the fabric. When the needles have been entirely inserted, their points and eyes will extend beyond the faces of the jaws and folder, where a suitable thread may be inserted through the eyes of both needles either by

hand or by suitable mechanism. The rock-shaft *h* will then be swung in the opposite direction, thereby drawing the needles backward through the work to draw the thread 5 through the work. In their passage the walls of the eyes of the needles will be forced toward each other, thereby diminishing the size of the eye and gripping the thread to draw the same into the fabric. After the needles 10 have completed their movement the jaws will be opened automatically by the cam-slots *f*, operating upon the jaw-carrying arms *d*. The thread may be severed by any suitable means after the needles have disengaged themselves 15 from the fabric.

Having described my invention, what I claim, and desire to secure by Letters Patent, is—

1. In a special sewing-machine the combination of a member *k* provided with teeth or corrugations on opposite sides thereof, movable carriers having teeth or corrugations adapted to mesh with the teeth or corrugations of the member *k*, means for simultaneously 25 meshing the teeth or corrugations of any individual carrier with the member *k*, and needle mechanism for effecting the sewing.

2. In a special sewing-machine, the combination of slotted means for maintaining a 30 fabric in a waved or undulated condition and a sewing-needle running in the slot having an eye whose walls are resilient and adapted to be bent by contact with the slot during the passage of the needle through the said slotted means in order to firmly grasp the thread by 35 the walls of the needle-eye.

3. In a special sewing-machine, the combination of a toothed member having teeth on opposite sides thereof, a plurality of movable 40 carriers each provided with a series of teeth adapted to coöperate with the toothed member on opposite sides thereof and to be moved simultaneously, means for moving the carriers and means for passing a needle into the 45 work operated by the carrier-moving means.

4. In a machine for providing an open-mouth fabric structure with a shirring-string at a single operation, the combination of a toothed member *k* having corrugations or 50 teeth on opposite sides thereof, a carrier one on each side thereof having a series of slotted teeth or corrugations coöoperating with the teeth or corrugations of the toothed member and means for moving the said carriers, whereby the teeth of the carriers are simultaneously meshed with the teeth of the toothed member and a sewing means for passing a shirring-thread through the work.

5. In a special sewing-machine, the combination of a toothed member having teeth on opposite sides thereof, oppositely-placed toothed jaws, cam mechanism for simultaneously moving the oppositely-placed toothed jaws to mesh them with the toothed member, 65 direct-acting lever mechanism and needle mechanism driven thereby, and a connection

between the lever mechanism and the means for moving the jaws.

6. In a special sewing-machine, the combination of a toothed member having teeth on opposite sides thereof, pivoted toothed jaws adapted to mesh therewith, a slotted cam-plate for swinging the pivoted jaws, needle mechanism and means for directly driving the needle mechanism. 75

7. In a machine for inserting shirring-strings in tubular fabric structures, the combination of a toothed member *k* having corrugations or teeth on opposite sides thereof, a pair of pivoted jaws provided with teeth or corrugations adapted to engage with the teeth or corrugations of the toothed member, a needle mechanism and means whereby the teeth of the carriers are simultaneously meshed with the teeth of the toothed member, comprising a shaft provided with cam means for swinging the pivoted jaws and with means for operating the needle mechanism. 80

8. In a machine for inserting shirring-strings in tubular fabric structures, the combination of a toothed member *k* having corrugations or teeth on opposite sides thereof, a pair of pivoted jaws provided with teeth or corrugations adapted to engage with the teeth or corrugations of the toothed member, a needle mechanism and a shaft, a slotted cam-plate carried by the shaft for operating a jaw and a connection between the shaft and the needle mechanism. 90

9. In a sewing-machine, the combination of a toothed member *k* having teeth on opposite sides thereof, a pair of corrugated fabric gathering or crimping jaws with actuating means therefor whereby the fabric may be crimped or gathered at a single operation, needle mechanism, and means whereby the teeth of the carriers are simultaneously meshed with the teeth of the toothed member, comprising a rock-shaft serving as a common operating means for the jaws and the needle mechanism. 100

10. In a sewing-machine, the combination of a toothed member *k* having teeth or corrugations on opposite sides thereof, a pair of toothed or corrugated fabric gathering or crimping jaws with actuating means to simultaneously mesh the teeth or corrugations of an individual jaw with the toothed member whereby the fabric may be crimped or gathered at a single operation and a needle mechanism. 115

11. In a machine for gathering the open mouth of a tubular or like structure, the combination of a slotted folder *k*, a plurality of movable toothed or corrugated carriers meshing therewith on different sides thereof and means for simultaneously meshing the teeth of any individual carrier with the folder. 120
